UNITED STATES PATENT OFFICE

102,634

DESIGN FOR A MOTOR VEHICLE MARKER LAMP OR SIMILAR ARTICLE

Matthew R. Korshin, Media, Pa., assignor to R. E.
Dietz Company, New York, N. Y.

Application May 4, 1936, Serial No. 62,464

Term of patent 7 years

To all whom it may concern:

Be it known that I, Matthew R. Korshin, a citizen of the United States, residing at Media, Delaware County, State of Pennsylvania, have invented a new, original, and ornamental Design for a Motor Vehicle Marker Lamp or Similar Article, of which the following is a specification, reference being had to the accompanying drawing, forming a part thereof.

In said drawing:

Fig. 1 is a perspective view of a motor vehicle marker lamp or similar article showing my new design.

Fig. 2 is a plan view thereof.

I claim:

The ornamental design for a motor vehicle marker lamp or similar article, substantially as shown.

MATTHEW R. KORSHIN.
